UNITED STATES PATENT OFFICE.

THOMAS S. WRIGHT, OF LANCASTER, OHIO.

DESIGN FOR A HEADLIGHT LENS.

Application filed April 14, 1924. Serial No. 9,251. Term of patent 14 years.

To all whom it may concern:

Be it known that I, THOMAS S. WRIGHT, a citizen of the United States of America, residing at Lancaster, in the county of Fairfield and State of Ohio, have invented a new, original, and ornamental Design for a Headlight Lens, of which the following is a specification, reference being had to the accompanying drawings, forming a part hereof.

Figure 1 is a front view showing my new,

original and ornamental design for headlight lens.

Figure 2 is a rear view thereof.

Figure 3 is a sectional view taken horizontally through the lens.

I claim:

The ornamental design for a headlight lens as shown.

THOMAS S. WRIGHT.
